UNITED STATES PATENT OFFICE.

HERBERT P. PAGE, OF BOSTON, MASSACHUSETTS.

DESIGN FOR AN EDIBLE ICE-CREAM CONTAINER.

Application filed March 3, 1924. Serial No. 8,807. Term of patent 3½ years.

To all whom it may concern:

Be it known that I, HERBERT P. PAGE, a citizen of the United States, and a resident of Boston, in the county of Suffolk and Commonwealth of Massachusetts, have invented a new, original, and ornamental Design for an Edible Ice-Cream Container, of which the following is a specification, refer-

ence being had to the accompanying drawing, forming part thereof.

The figure is a plan view of an edible ice cream container, showing my new design.

I claim:

The ornamental design for an edible ice cream container as shown.

HERBERT P. PAGE.
